ELECTRICAL TRANSFORMER

Lionel Lorant, Sunnyside, N. Y., assignor to Super
Electric Products Corp., Jersey City, N. J., a
corporation of New Jersey

Application October 15, 1940, Serial No. 361,202

2 Claims. (Cl. 175—361)

My present invention relates to electrical transformers.

It is found that reception by radio receiving apparatus is materially interfered with by the creation of noises due to electrical disturbances set up in current feed lines caused by the operation of electrical step-up transformers of neon sign and oil burner installations; said transformers receiving their primary current supply from said feed lines.

It is therefore the principal object of this invention, to provide an electrical transformer of novel and improved construction, the operation of which causes no such disturbances as above mentioned, that is, the operation of the transformer in no manner affects or disturbs the operation of the radio receivers.

I have ascertained that the real offending parts of the secondary system which cause electrical disturbances in the primary system of the transformer, meaning the disturbances desired to be avoided, are the internal leads to the secondary terminals together with the extensions of said leads on the secondary coil or coils up to the region of the core. It is the electrical emanations from these two short lengths of wire which affect the primary circuit, causing the trouble aforesaid.

I therefore resort to shielding the respective circuits of the transformer from each other in a novel, improved, simple, cheap and efficient manner, and what I do essentially to accomplish this, is shield only those portions of the components of the primary circuit which extend beyond that side of the core of the transformer, beyond which side said short lengths of secondary wire extend, employing the core proper as part of the shielding means, and thus effecting a substantial saving in the cost of construction and the labor involved in assembly. This, of course, is only one embodiment following the teachings of this invention.

I am aware that this invention is capable of numerous forms and various applications without departing from the essential features herein disclosed. It is therefore intended and desired that the specific constructions herein be deemed illustrative and not restrictive, and that the patent shall cover all patentable novelty herein taught; reference being had to the appended claims rather than to the particular description herein to indicate the scope of this invention.

In the accompanying drawing forming part of this application, similar characters of refer-

ence indicate corresponding parts in all the views.

Fig. 1 is a perspective view of an encased transformer, embodying the teachings of this invention.

Fig. 2 is a section taken along lines 2—2 in Fig. 1.

Fig. 3 is a perspective view of the transformer included in Fig. 1.

Fig. 4 is a view similar to Fig. 1, of a slightly modified structure.

Fig. 5 is a section taken along lines 5—5 in Fig. 4.

Fig. 6 shows a perspective of the transformer included in Fig. 4.

Fig. 7 shows another modification in transformer design in accordance with this invention.

In the drawing the numeral 15 indicates generally a shell type transformer, comprising a laminated core 16, on which is mounted a primary coil 17, and the secondary coils 18 and 19. This structure 15, is housed within the metal casing 20, which is of such dimensions that the core 16 acts as a partition forming the compartments 21 and 22; that is, said core is in substantial abutment with the side walls of the casing 20. It is evident that parts of both the primary and secondary coils reside in each of said casing compartments. It is preferred, but not mandatory, that the last portions of the last turns 18' and 19' of the secondary coils 18 and 19, and the internal secondary leads 18'' and 19'' shall be in one of the compartments, while the internal primary leads 17' shall be in the other compartment.

In this construction, only that portion of the primary coil 17 which is in the same compartment with the elements 18', 18'', 19' and 19'', is covered with a metallic member or shield 23; the core 16, acting as a shield for those portions of the components of the primary circuit which are within the compartment 22.

In the embodiment shown in Fig. 5, where one dimension of the core 16', is less than the analogous dimension of the casing 15', a metallic plate 24 extending from said core, serves to complete the partitioning of said casing to form the compartments 21' and 22'. Desiring to form a chamber 25, wherein the primary leads 17' may be connected to the current feed lines, I partition the chamber 21' with a metallic member 26, which thus acts as a shield against the offending elements 18', 18'', 19' and 19'' of the secondary circuit, for the primary leads 17' and the pri-

mary cable connection which could be effected through any of the openings by removal of one of the knock-out plugs 21. The primary current feed line cable is not shown. The removable plate 28, serves to cover the opening in the casing 18, through which the making of such connection is facilitated. The numeral 29, designates insulators for the primary lead wires 17, which wires, for good results may lie along the core 16. The secondary terminals are indicated by the numeral 38.

When the transformer is not of the shell type, as for instance shown in Fig. 7, the compartments or sections in the casing 31, are formed by a metallic extension 32, which forms with the core 32, the required partition.

It is to be noted that the core or its extensions forming the casing partition need not be in abutment with the walls of the casing, although desirable and expedient, abutment is not essential for proper operation.

Having set forth various embodiments of this invention, and desiring that the Letters Patent shall cover its teachings, as and for my invention,

I claim:

1. In a device of the character described, a trans-

former comprising a core having primary and unshielded secondary coils thereon, a metallic casing housing the transformer, metallic elements extending from the core portion carrying the coils, towards the walls of the casing, whereby the casing is substantially divided by the core into two compartments, a metallic member extending from the core and substantially partitioning one of said compartments into two chambers; said metallic member being positioned beyond the secondary coil portion remotest from the primary coil; parts of all the coils residing in the undivided compartment, and only in one of the chambers of the other compartment; the secondary internal terminal leans lying wholly within said chamber, and the primary internal terminal leads lying within the undivided compartment and extending only into the second of said chambers; the casing being provided with an opening into said second chamber for access to the primary leads, a closure member mounted on the casing for closing said opening, and a metallic shielding means on the primary coil.

2. A device as in claim 1, wherein the shielding means covers only that part of the primary coil which lies in the first chamber.

LIONEL LORANT.
